UNITED STATES PATENT OFFICE.

ISABELLA B. WHYTE, OF WOLSELEY, SASKATCHEWAN, CANADA.

MOP.

Application filed February 3, 1921. Serial No. 442,250.

To all whom it may concern:

Be it known that I, ISABELLA B. WHYTE, of the town of Wolseley, in the Province of Saskatchewan, Canada, have invented certain new and useful Improvements in Mops, of which the following is the specification.

The invention relates to improvements in mops and an object of the invention is to provide a general purpose mop specially constructed so that it can be used to advantage to get into corners, under and around radiators, stoves and other such household commodities.

A further object of the invention is to supply a comparatively large mop without making it unduly heavy or cumbersome.

A still further object is to construct the appliance so that the mop can be readily removed from the mop frame for cleaning and such like purposes, such arrangement also permitting of the use of a number of mops for different purposes such as for scrubbing floors, washing walls and ceilings and dusting.

A still further object of the invention is to construct the mop frame in a simple, durable and inexpensive manner and so that it can be easily and quickly made according to shop practice and such that the completed frame is extremely light yet strong.

A still further object of the invention is to provide the mop frame with an adjustable handle socket so that the mop handle can be adjusted in position in respect to the mop.

With the above more important objects in view the invention consists essentially in the arrangement and construction of parts hereinafter more particularly described and later pointed out in the appended claims, reference being had to the accompanying drawing in which:

Fig. 1 is a side view of the complete mop with the upper part of the handle broken away.

Fig. 2 is a plan view of the parts appearing in Fig. 1.

Fig. 3 is a side view of the frame.

Fig. 4 is a plan view thereof.

Fig. 5 is an enlarged detailed longitudinal sectional view through a part of the frame.

Fig. 6 is an enlarged detailed plan view of the frame showing the catch and associated parts.

In the drawing like characters of reference indicate corresponding parts in the several figures.

The frame of the appliance which embodies the part which carries the mop and that to which the handle is attached is now described in detail.

1 is a body or base plate which is provided with a pair of rigid parallel spaced equal length extension arms 2 and 3 which in the present instance are in the form of tubes, the outer or free ends of which are plugged as indicated at 4 and 5.

The plate 1 embraces the tubes having the edges thereof turned downwardly around the tubes and it is fastened to the same by riveting as indicated at 6. To the inner ends of the extensions or tubes I connect pivotally as by hinging at 7 the inner ends of a second pair of comparatively short extension pieces 8 and 9 also in the form of tubes which have their inner ends connected by a connecting plate 10 suitably riveted thereto. The outer ends of the latter tubes are also plugged and the adjacent ends of the base plate and the plate 10 are arranged in respect to the hinge so that when the tubes are axially aligned the said plates butt and form a natural and solid stop.

Any convenient releasable locking means can be employed for locking the tubes in the aligned position, such in the present instance embodying a spring pressed hooked latch 12 pivotally fastened at 13 to the plate 10 and having the hooked end arranged to overhang the plate 1 and engage with a catch 14 carried by the latter plate.

A stop pin 15 is provided on the plate 10 to limit the swinging of the latch under the action of the spring and the hooked end of the latch is tapered so that when the tubes are swung to the aligned or closed position the latch will automatically spring back and engage the catch 14.

The base plate is fitted with a pair of spaced upstanding guides 16 and 17 between which I mount pivotally a socket 18 which receives the handle 19, the handle being fastened in the socket in any suitable manner.

The lower end of the socket is connected to the guides by a pivot pin 20 and in a location above the pivot pin 20 I pass a second adjusting pin 21 through the socket and through similar guide slots 22 provided in the guides and formed concentric to the pin 20. In the present instance the ends of the pin 21 are fitted with guard washers 23 and the ends of the pin are enlarged to retain the washers in sliding contact with the outer

faces of the guides. The openings 20' in the sockets which receive the pin 20 are in the form of comparatively short slots so that the socket is permitted a limited end movement and advantage is taken of this to provide an adjustment in the handle in the following way.

The slots 22 are provided at the top ends and intermediate of their length with 10 notches 24 and the pins are connected by a coil spring 25 which normally draws the socket inwardly with the result that when the ends of the pin 21 reach any of the notches in the guide slots they escape into 15 the same and lock the socket against swinging in that position. Once locked the socket will remain so unless released by the attendant pulling the socket in a direction away from the base plate sufficiently to release 20 the pin 21 from the notches and then swinging it in the guide slots.

I have found in actual practice that by making the guide slots of a length such that the socket can swing through a right angle 25 and that by providing the two positions where the socket can be locked the mop can be adjusted to accommodate practically all conditions met with when operated.

The mop, or that part which actually contacts with the floor, wall or such like, is in reality in the form of a thrummed mat presenting a strong flexible canvas or such like 30 back 26 with strands of string or such like 27 stuck through it. The canvas back presents front and back pairs of pockets 28 and 35 29, 30 and 31 adapted to receive the tubes 2 and 3, 8 and 9 and is supplied with a closure flap 32 which can be suitably buttoned or otherwise releasably secured around the 40 guides and socket. Obviously the inner ends of the pockets are opened to allow of the entrance of the tubes into the same and the ends of the tubes are plugged as shown to prevent any tearing or unnecessary wearing 45 of the fabric.

When the mop is to be placed on the frame the latch is released and the tubes 8 and 9 are swung down to the position as shown in dotted outline in Fig. 5. The tubes 2 and 50 3 are then slipped into place in the pockets 28 and 29 and afterwards the tubes 8 and 9 are passed into the pockets 30 and 31. One then swings the tubes into alignment when they become automatically locked by the 55 catch and the mop is then positively fastened on the tubes. The flap 32 is then closed around the guides and socket simply to prevent the same from scratching or otherwise marring the furniture.

60 By observing the drawings it will be noticed that the mop handle has a position considerably towards one end of the frame and

that the frame is particularly narrow and thin. This arrangement allows one to get at inconvenient places such as under stoves, 65 under radiators and such like, as the mop structure is such that it can get under low lying articles and can reach well in beneath the same owing to the fact that the mop has, so to speak, a long end indicated 70 generally by the reference character 33.

At this point I wish particular attention to be given to the feature that my design of frame lends itself to getting at difficult 75 places which cannot be approached with other mops with which I am familiar as the frame work or head of such latter mops is too thick to conveniently go under say a radiator and not long enough to reach in far enough, if it does go under, to do a good 80 job.

By having the socket adjustable I can use this mop for washing or dusting walls and ceilings and the whole arrangement is particularly light yet strong and as it gives a 85 large mopping or dusting surface it will do the work, comparatively speaking, very quickly.

Whilst I have entered into a detailed description of the various parts, it will be 90 readily understood that they can be modified without departing from the spirit of the invention as set forth in the appended claims.

What I claim as my invention is:—

1. In combination a frame comprising 95 aligned long and short pairs of spaced arms, said arms being hinged together, an operating handle secured to the long arms adjacent the joint and a mop detachably connected to the arms and provided with pockets receiving the arms.

2. In combination a frame comprising aligned long and short pairs of spaced arms, 100 said arms being hinged together, an operating handle secured to the long arms adjacent the joint, a mop detachably connected to the arms and provided with pockets receiving the arms and means for releasably locking the arms in alignment.

3. In combination, a frame comprising 110 aligned long and short pairs of spaced tubular arms, said arms being hinged together, a catch releasably locking the arms in alignment, a handle adjustably secured to the long arms adjacent the joint and a mop detachably mounted on the arms and provided with pockets slidably receiving the same. 115

Signed at Wolseley, this 1st day of December 1920.

ISABELLA B. WHYTE.
